(57) **CLAIM**

The ornamental design for a dispenser, as shown and described.

DESCRIPTION

FIG. 1 is a top, front, and right side perspective view of a dispenser showing my new design;

FIG. 2 is a right side elevational view thereof; the undisclosed left side being a mirror image of that shown;

FIG. 3 is a front elevational view thereof;

FIG. 4 is an enlarged top plan view thereof;

FIG. 5 is a top, rear, and right side perspective view thereof, with the undisclosed left side being a mirror image of that shown, and the wall mount portion shown in an opened position; and,

FIG. 6 is an exploded top, rear, and right side perspective view thereof; with the undisclosed left side being a mirror image of that shown, the wall mount portion shown in an opened position, and the dispensing container portion shown detached from the wall mount portion.

The broken-line disclosure in the views is understood to represent portions of the article in which the claimed design is embodied, but which form no part of the claimed design.
